Primary Examiner—Robert C. Spangler

CLAIM

The ornamental design for a packaging tray for food or the like, substantially as shown and described.

DESCRIPTION

FIG. 1 is a side elevational view of a packaging tray for food or the like showing my new design;
FIG. 2 is an end elevational view;
FIG. 3 is a top plan view; and
FIG. 4 is a top perspective view with the lid removed.

FIG. 1.FIG. 2.FIG. 3.FIG. 4.
